(57) **CLAIM**

The ornamental design for the picatinny rail combined with M-lok rail, as shown and described.

DESCRIPTION

FIG. 1 is a top view of the picatinny rail combined with M-lok rail;

FIG. 2 is a top elevation view of FIG. 1;

FIG. 3 is a side view of FIG. 1, the left side being a mirror image;

FIG. 4 is a bottom view of FIG. 1;

FIG. 5 is a bottom-elevated view of FIG. 1; and,

FIG. 6 is a top view of FIG. 1.

Present design's intended use is for firearms accessory attachment.

The broken lines are shown to illustrate unclaimed portions of the invention and form no part of the claimed design.

1 Claim, 3 Drawing Sheets
